LAURENCE J. BERKELEY AND JOHN REID, JR., OF RACINE, WISCONSIN, ASSIGNEES
TO THE P & M COMPANY, OF CHICAGO, ILLINOIS, A CORPORATION OF ILLINOIS.

RAIL-ANCHOR.

1,355,302.

Specification of Letters Patent. Patented Oct. 12, 1920.

Application filed November 19, 1918, Serial No. 263,133. Renewed June 27, 1919. Serial No. 307,253.

To all whom it may concern:

Be it known that we, LAURENCE J. BERKELEY and JOHN REID, Jr., citizens of the United States, residing at Racine, in the county of Racine and State of Wisconsin, have invented certain new and useful Improvements in Rail-Anchors, of which the following is a specification, reference being had to the accompanying drawing, forming a part thereof.

This invention relates to devices for preventing the creeping or displacement of railway rails longitudinally as the result of traffic or other causes.

Its main objects are to maintain engagement or an initial grip of the anchor on a rail which will be increased by any tendency of the rail to creep in the direction of prevailing traffic; to prevent displacement by the jar or vibration produced by passing trains or by other causes of the anchor away from the tie or other part of the road bed against which it abuts; to facilitate the application of the anchor to a rail and its removal therefrom; and generally to increase the efficiency and improve the construction and operation of devices of this class.

It consists in the construction, arrangement and combination of parts as hereinabove particularly described and pointed out in the claims.

In the accompanying drawing like characters designate the same parts in the several figures.

Figure 1 is an inverted plan view of a rail anchor embodying the invention as applied to a rail base; Fig. 2 is a side elevation of the same, the rail base being shown in cross section; Fig. 3 is an end elevation of the anchor as viewed from the right relative to Figs. 1 and 2; and Fig. 4 is a perspective view on a smaller scale of a modified construction, a part of a rail to which the anchor is applied being indicated by dotted lines.

Referring to Figs. 1, 2 and 3, the anchor comprises a jaw member *a*, which may be made of malleable iron or other suitable material, and is fitted to hook over and engage with one edge of the base flange *b* of a rail, as shown in Fig. 2. At one end this member is formed with a vertical transverse

flange or abutment *c*, which is adapted to bear against the side of a tie or other stationary part of a road bed.

The anchor also comprises two oppositely acting transverse spring arms *d*, which are rigidly fastened at one end to the jaw member *a* and terminate at the other end in jaws *e*, which are adapted to be sprung into engagement with the opposite edge of the rail base at separated points thereon and stand in directions oblique to the points of attachment of the spring arms to the jaw member *a*, as shown in Figs. 1 and 3.

For the rigid attachment of the spring arms *d* to the jaw member *a*, the latter may be formed as shown in Fig. 3, with a transverse flanged opening in which the arms are inserted and fastened by a bolt or rivet *f*, or by other suitable means.

The spring arms *d* may be conveniently made from steel plate or flat bands of steel, and are bowed or bent, as shown in Fig. 1, to diverge from each other and extend obliquely across the bottom of the rail base from a point adjacent to the jaw member *a*.

To apply the anchor to a rail the jaw member *a* is hooked over one edge of the rail base with the abutment *c*, against one side of a tie or other stationary part of the road bed. The opposite ends of the arms *d* are then forced toward each other with tongs or other suitable tool, till the upwardly projecting jaws *e* will clear the edge of the rail base opposite that with which the jaw member *a* is engaged. The jaws are then raised into operative position and released, whereupon they are forced in opposite directions by the resiliency of the arms into engagement with the edge of the rail base.

Any tendency of the rail to creep toward the tie or other stationary part against which the abutment *c* bears, will tighten the grip of the jaw *e* adjacent to the abutment, due to the oblique disposition of the spring arm nearest the tie, without releasing the bite or grip of the other jaw *e* on the rail base.

Any tendency, due to jar and vibration produced by passing trains or resulting from other causes, of the anchor to shift on the rail away from the tie or other part of

the road bed against which it bears, will be prevented by the other or rearward jaw *e*, both of the jaws *e* coöperating with the jaw member *a* to firmly hold the anchor in place 5 on the rail base with the upper edges of the arms *d* bearing against the bottom of the base, as shown in Fig. 2.

To remove the anchor from a rail, the divergent ends of the arms *d* are swung toward each other with tongs or other suitable implement, thereby disengaging the jaws *e* from the edge of the rail base and permitting them to be dropped below it, whereupon the jaw member *a* is released and 15 can be readily disengaged from the other edge of the rail base.

Referring to Fig. 4, showing a modification of the anchor, the jaw member *a'* is formed integrally with the two spring arms 20 *d'* converging toward their opposite ends, which are formed with upwardly projecting jaws *e'* adapted to hook over the opposite edge of the rail base. With this one-piece form of the anchor, which is of approximately 25 horseshoe shape and is made from steel plate or heavy sheet steel, the bends *c'* of the arms *d'* adjacent to the jaw member *a'*, serve as abutments for engagement with the side of a tie or other stationary part of a road bed, to resist longitudinal displacement of the rail in either direction according to the position in which the anchor is placed relative to the tie or other stationary part against which it is to 30 bear.

This form of anchor is applied to a rail by spreading the ends of the spring arms *d'* till the hooked jaws *e'* will pass upwardly over and into engagement with the opposite 40 edge of the rail base from that with which the jaw *a'* is engaged. When the jaws *e'* are released, they are forced by the resiliency of the arms *d'* toward each other in opposite directions into engagement with 45 the rail base.

With this form of anchor the rearward arm *d'* and jaw *e'* farthest from the tie against which the anchor bears, act to prevent creeping of the rail toward the tie, the 50 grip of said jaw *e'* on the rail base being tightened by any movement of the rail toward the tie, on account of the oblique disposition of the arm *d'* relative to the rail.

The other arm *d'* with its jaw *e'* next to the tie, prevents displacement of the anchor away from the tie and coöperates with the other arm and jaw *e'* to hold the anchor firmly in place on the rail.

Various modifications other than those 60 shown and specifically mentioned may be made in the construction and arrangement of parts of the anchor without departing from the spirit and scope of the invention as defined in the following claims.

65 We claim:

1. A rail anchor comprising a jaw adapted to engage with one side of a rail base, and oppositely acting spring arms terminating in jaws adapted to be sprung into engagement with the other side of the rail base. 70

2. A rail anchor comprising a jaw adapted to engage with one edge of a rail base, and two transverse oppositely acting spring arms adapted to extend obliquely across the bottom of the rail base and terminating in jaws adapted to be sprung into engagement with the opposite edge of the rail base. 75

3. A rail anchor comprising a jaw member adapted to engage with one edge of a rail base and provided with an abutment adapted to bear against a stationary part of a road bed, and two oppositely acting transverse spring arms rigidly fastened at one end to the jaw member and terminating at the other end in jaws which are adapted to 85 be sprung into engagement with the opposite edge of the rail base. 80

4. A rail anchor comprising a jaw member adapted to engage with one edge of a rail base and formed with an abutment 90 adapted to bear against a stationary part of a road bed, and two oppositely acting divergent spring arms rigidly fastened at one end to said jaw member and terminating at the other end in jaws adapted to be sprung 95 into engagement with the opposite edge of the rail base at separated points therein.

5. A rail anchor comprising a malleable iron jaw member adapted to engage one edge of a rail base and a spring element having 100 a permanent connection therewith at one end and provided at the other end with means for engaging the other edge of the rail base; said spring element extending diagonally across the rail base and adapted to 105 be strained in its application to the rail.

6. A rail anchor comprising means for engaging one edge of a rail base and a plurality of spring elements associated therewith for engaging the other edge of the rail 110 base; said spring elements being adapted to be strained in their application to the rail and to bear with spring pressure against the edge thereof.

7. A rail anchor comprising means for engaging one edge of a rail base and a plurality of spring elements secured thereto for engaging the other edge of the rail base; said spring elements being adapted to be strained in their application to the rail and 115 to bear with spring pressure against the edge thereof.

8. A rail anchor comprising a jaw member for engaging one edge of a rail base, and a plurality of spring elements associated 120 therewith, which extend obliquely across the rail base, and engage the opposite edge of the same; said spring elements being adapted to be strained in their application to the rail. 125

9. A rail anchor comprising a jaw member for engaging one edge of a rail base, and diverging spring elements associated therewith, which extend obliquely across the rail base, and engage the opposite edge of the same; said spring elements being adapted to be strained in their application to the rail. 5
10. A rail anchor comprising a jaw member for engaging one edge of a rail base, and 10 spring elements associated therewith which extend obliquely across the rail base at an angle to each other, and engage the opposite edge of the same; said spring elements being strained in opposite directions in their 15 application to the rail.
11. A rail anchor comprising a jaw member for engaging one edge of a rail base, spring arms secured thereto and diverging one from the other from the point of their 20 attachment of the jaw member; the spring arms being formed with jaws for engaging the opposite edge of the rail base and being adapted to be strained in the application of the anchor to the rail.
12. A rail anchor comprising a jaw member for engaging one edge of a rail base, spring arms secured thereto and diverging one from the other from the point of their 25 attachment of the jaw member; the spring arms being formed with jaws for engaging the opposite edge of the rail base and adapted to be strained in opposite directions in the application of the anchor to the rail.
13. A rail anchor comprising a jaw member for engaging one edge of a rail base, spring arms secured thereto and curved oppositely whereby they diverge one from the other from the point of their attachment 30 of the jaw member; the spring arms being formed with jaws for engaging the opposite edge of the rail base and adapted to be strained by pressing them one toward the other during the application of the anchor to the rail.
14. A rail anchor provided with a tie abutting portion and with a pair of divergent resilient members adapted to engage the rail and check relative longitudinal movements, as between rail and anchor, in 35 either direction.
15. A rail anchor provided with a tie abutting portion and with a pair of oppositely acting springs adapted to engage the rail and check relative longitudinal movements, as between rail and anchor, in 40 either direction.
16. A rail anchor provided with a tie abutting portion and with a pair of spring arms disposed obliquely of the rail and engaging the same which are oppositely acting to check relative longitudinal movements, as between rail and anchor, in either direction. 45
17. A rail anchor comprising a tie abutting member adapted to engage one edge 50 of the rail base of a rail, and a pair of oppositely acting spring arms adapted to engage the other edge of such rail base to check relative longitudinal movements, as between rail and anchor, in either direction. 70
18. A rail anchor comprising a tie abutting member and a pair of oppositely acting members extending diagonally under and across and engaging the rail to check 75 relative longitudinal movements, as between rail and anchor, in either direction.
19. A rail anchor comprising a tie abutting member and a pair of oppositely acting members engaging the rail by spring 80 pressure to check relative longitudinal movements, as between rail and anchor, in either direction.
20. A rail anchor comprising a tie abutting member adapted to engage one edge of 85 the base of a rail and a pair of members engaged with said tie abutting member and extending obliquely under and engaging the opposite edge of the rail base which act to check relative longitudinal movements, as 90 between rail and anchor, in either direction, one member checking such movement in one direction and the other in the other direction.
21. A rail anchor comprising a tie abutting member adapted to engage one edge 95 of the base flange of a rail and a spring arm engaged therewith and extending under the rail base and curved toward the tie against which the anchor bears and formed 100 at its free end with a jaw to engage the other edge of the rail base.
22. A rail anchor provided with means for bearing against a tie and comprising means engaging one edge of the rail base 105 and having a pair of divergent spring members extending under the rail base and engaging the other edge thereof.
23. A rail anchor provided with means for bearing against a tie and comprising 110 means engaging one edge of the rail base and having a pair of divergent spring members extending under the rail base and engaging the other edge thereof at points respectively nearer and more remote from the 115 tie than the place of engagement of said first named engaging means.
24. A rail anchor comprising means for engaging one edge of the rail base and provided with a pair of spring arms oblique 120 with respect to each other which extend under the rail base and engage the other edge thereof.
25. A rail anchor comprising means for engaging one edge of the rail base and for 125 bearing against a tie, and provided with a pair of spring members divergent therefrom and extending under the rail base and engaging the other edge thereof.
26. A rail anchor comprising means for 130

engaging one edge of the base of a rail and a pair of spring arms extending therefrom under the rail base and engaging the other edge thereof.

5 27. A rail anchor engaged with the rail base at one side and provided with two spring members extending under the rail

base and engaging its other edge which are bent in application of the device to the rail.

LAURENCE J. BERKELEY.
JOHN REID, JR.

Correction in Letters Patent No. 1,355,302.

It is hereby certified that in Letters Patent No. 1,355,302, granted October 12, 1920, upon the application of Laurence J. Berkeley and John Reid, Jr., of Racine, Wisconsin, for an improvement in "Rail-Anchors," an error appears in the printed specification requiring correction as follows: Page 3, line 80, claim 19, after the word "members" insert the clause *extending diagonally under and across and*; and that the said Letters Patent should be read with this correction therein that the same may conform to the record of the case in the Patent Office.

Signed and sealed this 30th day of November, A. D., 1920.

[SEAL.]

L. B. MANN,

Acting Commissioner of Patents.
